UNITED STATES PATENT OFFICE

WILLIAM L. ROESSNER, OF DENVER, COLORADO

FUSIBLE LINK

Application filed September 8, 1931. Serial No. 561,667.

This invention relates to improvements in fusible links of the type employed in connection with fire extinguishing apparatus and fire doors.

In large office buildings and factories, it is customary to provide stair wells and elevator shafts extending from the top of the building to the bottom and at each floor there are door openings through which entrance may be had to the stairway and into the elevator, and these openings are provided with heavy fire doors that are biased to closed position by means of weights or springs and are held in open position by means of a fusible link that is so constructed that it will fail when the temperature reaches a predetermined value.

It quite frequently happens that with the ordinary type of fusible link, fire doors and other apparatus that is held in open position by fusible links will be released at times when there is no occasion for them to move and this aside from the inconvenience that it causes, is frequently the cause of serious accidents.

It is one of the objects of this invention to produce a fusible link of such construction that it can be relied upon at all times to perform its function and which will resist very large forces in comparison with its size.

Links of the type to which this invention relates, and which will be described herein, can be used in many different places, but the specific link shown and described will be illustrated as applied to a fire door; but it is to be understood that its use is not to be limited in any way by this illustration.

This invention briefly described, consists of a fusible link structure comprising a plate having an opening and a cooperating part formed of two parallel arms that extend through the opening in the plate and are then spread apart and held in spread position by means of a plug of easily fusible solder. When a force is applied which tends to remove the arms from the plate, this force will be resisted by the outwardly inclined ends which are held against inward movement by the plug. Since the plug is subjected only to compressive strains, it will

positively resist very large forces without danger of failure as distinguished from links that are held together by easily fusible solder and in which the strains are resisted by the tensile strength of the solder.

In order to describe this invention so that it can be most readily understood, reference will be had to the accompanying drawing in which it has been illustrated in its preferred form, and in which:

Fig. 1 is a section through a fire wall showing a fire door held in open position by the fusible link that forms the subject of this invention;

Fig. 2 is a side elevation of the improved link;

Fig. 3 is a section taken on line 3—3, Fig. 2;

Fig. 4 is a view showing the parallel arms that forms one part of the link; and

Fig. 5 shows a slightly different embodiment of the invention.

In the embodiment of the invention shown in Figs. 2 and 3, a casing comprising a tube 1 has been shown. One end of this tube is closed by a transverse member 2 that has an opening 3 for the reception of the hairpin like structure shown in Fig. 4. This structure consists of a flexible piece of steel ribbon that is bent double. The ends 4 are curved outwardly for a short distance and the extreme tips are bent inwardly as indicated by reference numeral 5. Located within the tube 1 is a spring 6 and secured to the open end of the tube is a bail 7. This bail may be held in place by means of rivets 8 or it may be welded or otherwise secured to the tube. A washer 9 is provided with a rectangular opening and this is threaded onto the inner end of the structure shown in Fig. 4. After the ends 4 have been passed through the washer 9, a plug 10 of easily fusible solder is put into place between the end portions 4 and holds them spread apart to such an extent that they will no longer pass through the opening in the washer.

The assembly shown in Figs. 2 and 3 can be subjected to a considerable force tending to separate the flexible arms from the remainder thereof without danger of the parts failing because the force is resisted by the

plug 10, which, although it is easily fusible, is composed of solid material that will not readily crush. In Fig. 1 an assembly like that just described has been anchored at one end to the wall 11 and at the other end to the fire door 12. This door is biased to closed position by means of a cable 13 and a weight 14. Or, if the cable and weight are not desired, they can be replaced by a spring which exerts a force tending to close the door. If a fire breaks out in the building, or if the temperature rises for any reason until it exceeds the temperature necessary to fuse the plug 10, the parts can then be easily separated because the arms of which portions 4 form a part, are made very flexible and unless they are held separated by some solid material, they will offer very small resistance against compression. Where the parts are constructed as shown in Figs. 2 and 3, the spring 6 will function to push the washer 9 over the ends 4 as soon as the plug has melted and this assists to some extent in the operation of the device. Another function for spring 6 is that when this spring is used, the fusible plug will be held in place with greater security than if the spring were not in use, and therefore the fusible links can be shipped in fully assembled condition which assures that they will be correctly assembled, as the assembling can be done at the factory.

In Fig. 5 I have shown a slightly different form of the invention. The main difference between that shown in Fig. 5 and what is shown in Figs. 2 and 3, is that in Fig. 5, the tube 1 has been omitted and the bail 7 has its ends attached to a perforated transverse portion 15 that corresponds to the washer 9 in Fig. 3. A washer 16 takes the place of bottom 2 in Fig. 3. The fusible plug is provided with grooves on opposite sides and these grooves are of the proper depth and width to receive the ends 4. The fusible plug is securely held in place due to the grooves and to the action of the spring.

From the above description it will be apparent that the simple construction shown and described results in a very dependable fusible link that will resist high strains without danger of prematurely failing and it is therefore especially well adapted for use with fire protective apparatus of all kinds such as the fire doors to which reference has been made and automatic sprinkler systems as well as other types of fire extinguishing apparatus.

Having described the invention what is claimed as new is:

1. A fusible link for use in controlling temperature responsive apparatus, comprising in combination, a member having an opening, a second member having two substantially parallel arms adapted to pass through the opening, the ends of the arms being in-

clined outwardly so as to be spaced farther apart than the width of the opening, and a plug of readily fusible material interposed between the ends of the arms to hold them in spread relation and thereby prevent their withdrawal through the opening.

2. A fusible link for use in controlling temperature responsive apparatus, comprising, in combination, a member having an opening, a second member having two substantially parallel arms adapted to pass through the opening, the ends of the arms being inclined outwardly so as to be spaced farther apart than the width of the opening, a plug of readily fusible material interposed between the ends of the arms to hold them in spread relation and thereby prevent their withdrawal through the opening and means for forcing the member having the opening against the inclined outer surfaces of the arms whereby the latter will be forced against the outside of the plug.

3. A fusible link of the type described, comprising, in combination, two relatively movable and separable members, one of which comprises a member provided with an opening and the other of which comprises two substantially parallel flexible arms, one end of the arms being attached to each other and the other end extending through the opening in the other member, the ends that extend through the opening being spread apart so that the distance between their outer surfaces is greater than the corresponding width of the opening, and a plug of fusible material interposed between the spread ends.

4. A fusible link of the type described, comprising, in combination, two relatively movable and separable members, one of which comprises a member provided with an opening and the other of which comprises two substantially parallel flexible arms, one end of the arms being attached to each other and the other end extending through the opening in the other member, the ends that extend through the opening being spread apart so that the distance between their outer surfaces is greater than the corresponding width of the opening, a plug of fusible material interposed between the spread ends and resilient means associated with the parts for producing a force tending to withdraw the arms from the opening.

5. A fusible link of the type described, comprising, in combination, a tubular member having one end provided with a bottom and the other end open, the bottom having an opening, a helical spring in the tubular member, the length of the spring being greater than that of the tubular member whereby when one end of the spring rests on the bottom, the other end will extend to the outside of the tubular member, a member comprising two substantially parallel resilient arms extending through the tubular member and

through the spring, the ends of the arms being bent so as to be outwardly inclined, a plate having an opening, said plate being located at the outer end of the spring, the ends of the arms extending through the opening, and a plug of fusible material located between the outer ends of the arms.

6. A fusible link of the type described, comprising, in combination, a tubular member having one end provided with a bottom and the other end open, the bottom having an opening, a helical spring in the tubular member, the length of the spring being greater than that of the tubular member whereby when one end of the spring rests on the bottom, the other end will extend to the outside of the tubular member, a member comprising two substantially parallel resilient arms extending through the tubular member and through the spring, the ends of the arms being bent so as to be outwardly inclined, a plate having an opening, said plate being located at the outer end of the spring, the ends of the arms extending through the opening, a plug of fusible material located between the outer ends of the arms, and means for anchoring the plug in place.

In testimony whereof I affix my signature.

WILLIAM L. ROESSNER.
